GAME BOARD

Kean C. Angelus, Washington, D. C.

Application January 12, 1949, Serial No. 205

Term of patent 7 years

(Cl. D34—5)

To all whom it may concern:

Be it known that I, Kean C. Angelus, a citizen of the United States, residing at Washington, in the District of Columbia, have invented a new, original, and ornamental Design for a Game Board, of which the following is a specification, reference being had to the accompanying drawing, forming a part hereof.

The single figure is a top plan view of a game board, showing my new design.

The board is of conventional thickness. The surface of the board is flat and ornamented with surface markings only. The back of the board is plain or of conventional appearance.

The dominant features of my new design are shown in solid lines in the drawing.

I claim:

The ornamental design for a game board, as shown and described.

KEAN C. ANGELUS.
